INK CLEANING DEVICE FOR FLAT BED CYLINDER PRINTING PRESSES

Filed April 26, 1927

Patented Mar. 20, 1928.

UNITED STATES PATENT OFFICE.

BOARDMAN J. HILL, OF DES MOINES, IOWA.

INK-CLEANING DEVICE FOR FLAT-BED CYLINDER PRINTING PRESSES.

Application filed April 26, 1927. Serial No. 186,690.

My invention relates to and consists in certain improvements in means for readily, quickly and easily removing ink from the flat beds of cylinder printing presses of the kind illustrated and described in my companion application for patent filed November 22, 1926, Serial Number 150,023.

My object is to provide means whereby the ink cleaner may, when at one end of the flat bed stroke, and when immediately over the ink trough, be swung downwardly into the trough so that the sharp edge scraper at the outer end of the trough may engage the cleaner relatively high up above the part thereof which is usually covered by ink, and to thereby remove all of the ink from the cleaner blade, and to thereby prevent any of the ink from said blade dripping upon the flat bed plate during its subsequent movement.

Another object is to provide improved means of simple, durable and inexpensive construction, whereby the operator can readily, quickly and easily adjust the cleaner blade operating device to its position for operating as a cleaner or to an inoperative position.

My invention consists in the construction, arrangement and combination of the various parts of the device, whereby the objects contemplated are attained, as hereinafter more fully set forth, pointed out in my claims, and illustrated in the accompanying drawings, in which:

Figure 1 shows a vertical, central, longitudinal, sectional view of a portion of a flat bed cylinder printing press of ordinary construction, having my improvement applied thereto.

Figure 2 shows a detail, vertical, sectional view through one portion of the flat bed plate with the ink trough connected therewith. The position of the ink cleaner is shown by solid lines directly over the discharge end of the trough, and by dotted lines in position just ready to leave the top of the flat bed plate.

Figure 3 shows an enlarged, detail, sectional view through the central portion of the rod for connecting the cam with the lever that operates the cleaner blade.

Figure 4 shows a detail perspective view illustrating the means for lengthening or shortening the rod which connects the cam to the cleaner operating lever.

Figure 5 shows an enlarged, detail, sectional view of the spring actuated slide bolt in the crank for adjusting the length of the operating bar; and

Figure 6 shows a detail perspective view of a portion of the flat bed plate with the ink trough attached thereto.

Referring to the accompanying drawings, I have used the reference numeral 10 to indicate generally the frame of the printing press. Slidably mounted upon this frame is a type form bed 11 connected with the ink distributing plate 12. The sliding movement is usually effected in presses of this kind by means of a rack 13 applied to the form bed and ink distributing plate, and in mesh with a cog wheel 14 to which an alternating rotary motion is applied in the ordinary manner. At one end of the press there is usually provided an ink receptacle 15 in which there is mounted an ink distributing roller 16, which is rotated during the operation of the press.

In presses of this kind there is also usually provided an ink carrying roll 17 mounted on a bell crank lever 18 connected to a rod 19 which in turn is reciprocated by a part of the operating mechanism of the printing press in any ordinary manner not specifically shown herein. This ink carrying roll 17 moves from position in contact with the roll 16 to position in contact with the ink distributing plate.

Presses of this kind are also usually provided with a series of ink distributing rollers, usually arranged in groups of three, there being two soft surfaced rollers 20 in contact with the ink distributing plate, and a hard surfaced roller 21 contacting with the two soft surfaced rollers of the group.

In presses of this kind there is usually supplied a series of form inking rollers similar in character and arrangement with the ink distributing rollers, the soft surfaced rollers being indicated by the numeral 22 and the 100 contacting hard surfaced roller by the numeral 23, the soft surfaced rolls being in position to be engaged at times by the flat ink distributing plate, and at other times to transmit the ink thereon to the type 105 forms.

All of the parts previously described are of common construction and of themselves form no part of my present invention, and have been herein illustrated and described 110

to show the manner in which my invention is applied to an ordinary flat bed cylinder printing press.

- My improvement comprises a rock shaft 24 mounted in suitable bearings in the frame 10 above the ink distributing plate. Fixed to the shaft 24 is an upwardly extended arm 25 to which is attached a contractile coil spring 26, which is fixed at its other end to a part of the frame. Extending downwardly from the shaft 24 is an arm 27 to which there is detachably fixed a cleaner 28. This cleaner extends transversely across the printing press the full width of the ink distributing plate and is made of two metal plates with two rubber strips between them. The rubber strips project downwardly below the metal plates, and one is preferably longer than the other, as clearly shown at 29 in Figure 2. At one end of the shaft 24 is a downwardly extending lever 30, and pivoted to the lower end of the lever 30 is a rod member 31 adjustably and slidably connected to a second rod member 32, which is provided at its lower end with a roller 33. This roller is designed to engage a cam 34 fixed to a shaft 35, mounted in the frame 10 and rotated by mechanism connected with the press and not shown.
- For the purpose of adjusting the rods 31 and 32 relative to each other, and for securing them in adjusted position, I have provided the following mechanism:
- Extended through the rod 31 are two bolts 36, which also extend through slots 37 in the rod member 32, thus permitting the rod member 32 to slide longitudinally relative to the rod member 31. Rotatively mounted in the rod member 31 is a shaft 38 provided with a crank 39. This crank 39 has a hollow handle 40 in which is a spring operated slide bolt 41. One end of the slide bolt is provided with a knob 42 by which the operator can readily grasp the slide bolt and move it outwardly. The bar 31 has two openings 43 designed to receive the end of the slide bolt to thereby hold the crank 39 in either one of two adjusted positions. Formed in the bar member 32 is a rectangular vertical slot 44 in which is slidably mounted a block 45. This block is pivoted at 46 to a crank 47, which in turn is fixed to the shaft 38, as shown in Figure 4. When the shaft 38 is rotated through a half revolution, then the crank 47 is also rotated through a half revolution, and the slide block 45 attached to the crank will move up and down in its slot, but at the same time will move the rod member 32 longitudinally, and when the crank 39 has moved through a half revolution, its spring bolt will then enter the corresponding opening 43, and thus locking the bar in its adjusted position. When the bar is in one of its adjusted positions, and during the rotation of the cam

34, the cam will engage the roller 33 and move the bar, thereby causing the cleaner blade 28 to move from position above the plate 12 when the plate is moved to the right, as shown in Figure 1, and it will cause the cleaner to move downwardly into engagement with the plate 12 when the latter is moving toward the left, as shown in Figure 1.

Mounted upon the outer end of the plate 12 is an ink trough indicated generally by the reference numeral 48. Its top is substantially flush with the top of the plate 12, and its outer end stands spaced from the end of the plate 12, and is formed with an upwardly and inwardly inclined relatively sharp blade 49.

Formed on the cam 34 is a supplemental cam member 50, the purpose of which is as follows: When the plate 12 has moved toward the left, as shown in Figure 1, to about the position shown in Figure 2, that is to say, when the end of the plate is directly under the cleaner 28, then the supplemental cam member 50 engages the roller 33, and swings the cleaner downwardly through an arc until the cleaner stands in substantially upright position, as shown by solid lines in Figure 2, at which time the cleaner blade will be in engagement with the blade 49 of the ink trough. This will cause the flexible cleaner blade to enter deeply into the trough, and the blade 49 will then engage the flexible cleaner blade above the point where the ink is carried by the flexible cleaner blade. Then during a further movement of the plate 12 to the left, as shown in Figure 2, the ink will all be removed from the flexible cleaner blade and deposited in the trough. Heretofore in devices in which this extra cam 50 has not been employed, it sometimes happens that all of the ink is not removed from the flexible cleaner blade by the blade 49, and hence during the other movements of the plate 12, the ink will drip upon it, but with my improvement and by causing the flexible cleaner blade to move through an arc downwardly into the trough, this difficulty is wholly obviated.

I claim as my invention:

1. The combination with a printing press having a flat ink distributing plate and a series of ink distributing and form inking rollers, of a flexible cleaner above the flat ink distributing plate, means for moving the cleaner into engagement with the flat ink distributing plate during the movement of said plate in one direction and elevating said cleaner out of engagement with the said ink distributing plate during the movement of the latter in the opposite direction, a trough shaped ink receptacle attached to one end of the ink distributing plate in position to receive ink scraped from the said plate and of such size as to permit the flexible cleaner

to move downwardly into the trough after the end of the ink distributing plate passes the cleaner, the side of the trough opposite from the adjacent edge of the ink distributing plate being formed into a blade to engage the side of the cleaner and remove ink therefrom and discharge it into the trough, and means for causing the flexible cleaner to swing downwardly through an arc as it passes through the trough and to approach a substantially vertical position when it engages the blade at the side of the trough opposite from the ink distributing plate.

2. The combination with a printing press having a flat ink distributing plate and a series of ink distributing and form inking rollers, of a cleaner above the flat ink distributing plate, and means for automatically moving the cleaner into engagement with the flat ink distributing plate during the movement of said plate in one direction and elevating said cleaner out of engagement with said ink distributing plate during the movement of the latter in the opposite direction, said means comprising a pivotal support for the cleaner, an arm fixed to the cleaner, a rod pivoted to the arm, a rotatable cam to engage said arm and cause it to be moved in unison with the action of the cam, said rod being formed of two parts slidably connected with each other, means for securing the rod in either of two positions, one position permitting the cam to operate the rod and the other position holding the rod out of engagement with the cam, a supplemental cam member connected with said cam and arranged to engage said roller in such manner as to cause the said cleaner to swing downwardly through an arc just after the ink distributing plate has passed beneath the cleaner, a trough fixed to the ink dis-

tributing plate through which the said cleaner may thus swing during its operation by the supplemental cam member, and a cleaner blade at the outer end of the ink distributing trough to engage said cleaner and remove the ink therefrom after the cleaner has passed through the trough.

3. The combination with a printing press having a flat ink distributing plate and a series of ink distributing and form inking rollers, of a cleaner above the flat ink distributing plate, and means for automatically moving the cleaner into engagement with the flat ink distributing plate during the movement of said plate in one direction and elevating said cleaner out of engagement with said ink distributing plate during the movement of the latter in the opposite direction, said means comprising a pivotal support for the cleaner, an arm fixed to the cleaner, a rod pivoted to the arm, a rotatable cam to engage said arm and cause it to be moved in unison with the action of the cam, said rod being formed of two parts slidably connected with each other, and means for securing the rod in either of two positions, one position permitting the cam to operate the rod and the other position holding the rod out of engagement with the cam, said means comprising a shaft rotatively mounted in one of the rod members, a lever on the shaft, a handle on the lever, a spring bolt connected with the handle, said rod having openings to receive the spring bolt in its different positions of movement, a crank on said shaft, a slide bar pivoted to the crank, said other bar member being formed with a slot in which said slide bar is slidably mounted, for the purposes stated.

Des Moines, Iowa, April 14, 1927.
BOARDMAN J. HILL.
